6 Claims. (Cl. 179—100.41)

The present invention relates to electromagnetic devices and to methods of making same, and pertains more particularly to electromagnetic-acoustic devices.

5 The invention will be described in connection with electromagnetic sound devices for recording, but can be also applied to reproducing devices, etc.

Devices according to the invention are especially well adapted for use in the method of sound recording described in U. S. Patent No. 1,919,116 to J. A. Miller.

In the various electromagnetic devices, for example loudspeakers, pickups and the like in which an armature moves within a magnetic field created between pole pieces, it is highly important for proper operation that the armature be accurately spaced from the faces of the pole pieces. It is also important that the spaces be easily obtained and once obtained be maintained irrespective of shocks and vibrations. Furthermore, it is important that the device be easy to assemble and disassemble even by not highly skilled persons and that the proper distancing of the armature from the pole pieces be effected without requiring a special device.

In accordance with the invention the pole pieces of the device are rigidly secured to members of nonmagnetic material, which members are provided with surfaces upon which the armature is suspended; the pole faces and the surfaces of suspension lying in the same plane.

It is necessary that the pole pieces be rigidly secured to the members of nonmagnetic material so that their relative position thereto will not be influenced by shock and vibration, and it is preferable that the pole faces and the suspension surfaces be finished in one operation so as to lie in the same plane.

40 In a particular embodiment of the invention the armature and its means of suspension form a single piece of magnetic material of uniform thickness. In such a case the armature is mounted on the surface of the nonmagnetic member to which the pole piece is secured, with the interposition of suitable spacers. In this embodiment of the invention the distance between the armature and the pole piece is governed only by the thickness of the spacer.

50 Our invention will be more fully described in connection with the specific example illustrated in the drawings which form part of the specification, and in which,

55 Figure 1 is a side elevation of an electromag-

netic recorder in accordance with the invention partly sectionized along line I—I of Fig. 2;

Figure 2 is a side view of Figure 1 partly sectionized along the line II—II of Fig. 1;

Fig. 3 is a partly sectionized plan view of the recorder shown in Figure 1 with the upper pole piece assembly removed;

Fig. 4 is a perspective view of one of the pole pieces shown in Figs. 1 and 2, and

Fig. 5 is an exploded perspective view of the recorder of Fig. 1 with the coils omitted for simplicity.

Referring to Figure 1, the electromagnetic recorder consists of two pole piece assemblies A—A, each comprising a U-shaped member 7 of non-magnetic material, for instance copper, and is provided with two plane end-faces 9—9 serving to support an armature 1 of magnetic material. Rigidly secured to each of the members 7—7—for instance by screws, clamping, soldering, or welding—is a pole piece 6 (see Fig. 4) of U-shaped cross section and forming two poles 18—18, having pole faces 8—8.

After the pole piece 6 has been secured to the member 7, the pole faces 8—8 and the faces 9—9 are finished so as to lie in the same plane, this being preferably effected in a single operation, for instance by so milling or grinding the faces 8—8 and 9—9 that they lie exactly in the same plane.

The armature 1 (see Figs. 3 and 5) is formed of a flat piece of magnetic material of uniform thickness, for instance of soft iron. Its central portion 2 is substantially square and projects on one side in a centrally extension 3, to which a recording cutter or needle 16, is removably secured by means of a screw 17. The square 2 of the armature 1 extends on each side into narrow neck portions 4—4 to end in two rectangular suspension portions 5—5 which are provided with clearance holes 20—20.

The portions 4—4 serve to provide the torsional forces to the armature; when in operation the armature portion 2 tends to vibrate about the longitudinal axis of the portions 4—4.

Arranged one on each side of the portions 4—4 and encircling the portion 2 with a clearance sufficient to prevent any contact therewith, are two coils 12—12. In the case of a recording device as illustrated the coils 12—12 carry the impressed amplified current, whereas for reproducing devices such coils carry the induced current. In either case the coils may be in series or in parallel.

The coils 12—12 are secured in a fixed position, for example by means of a wooden wedge 13,

which forces the coils against the inner sides of the poles 18-18, (see Fig. 2).

The pole piece assemblies A-A are arranged with their respective faces 9-9 opposing each other with the interposition of the armature 1; the latter being spaced from the faces 9-9 by spacers 10. The whole device is secured together into a rigid unit by four bolts 11, passing through the clearance holes 20 of the armature, and 10 through corresponding bores in the members 7-7 and in spacers 10.

In the device shown the distance between the surfaces of the armature portion 2 and the pole faces 8-8 is determined by the thickness of the 15 spacers 10-10, and due to this the device may be quickly and accurately assembled or taken apart and reassembled without requiring special tools or skill.

For mechanical recording the armature 1 should be comparatively rigid and for this purpose, as has been shown, is made integral with 20 its means of suspension and has the same thickness. However, in other electromagnetic devices, for instance loudspeakers, the armature is preferably suspended in a less rigid manner. For this purpose, the portions shown as 4-4 and 5-5 25 can be made of different material from that of the central portions 2, whereby portions 4-4 and 5-5 are rigidly secured to the central portion, 30 for instance by soldering or welding.

The magnetic field in which the armature vibrates may be supplied by a permanent magnet 14, secured in good magnetic contact with the pole pieces 6-6 by means of screws 15-15. 35 While the magnet 14 is shown as having the shape of a bar, magnets of other shapes, for example horseshoe magnets, may be also used. Instead of using a permanent magnet, an electromagnet may also be used, in which case a source 40 of supply for energizing the electromagnet is required.

While we have described our invention in regard to specific examples and in specific applications, we do not wish to be limited thereto, but 45 desire the appended claims to be construed as broadly as permissible in view of the prior art.

What we claim is:

1. An electromagnetic device comprising, a coil, means for producing a magnetic field, a member 50 of non-magnetic material having supporting surfaces lying in a common plane, a pole piece rigidly secured to said member and having pole faces lying in the plane of said supporting surfaces, an armature adjacently disposed to said pole faces, and means for suspending said armature from the supporting surfaces of said member.

2. An electromagnetic device comprising, a coil, means for producing a magnetic field, a member 55 of non-magnetic material having supporting surfaces lying in a common plane, a pole piece rig-

idly secured to said member and having pole faces lying in the plane of said supporting surfaces, an armature disposed adjacent to said pole faces, and means including spacers for suspending the armature from the supporting surfaces 5 of said member.

3. An electro-acoustic device for cutting a sound track on a film carrier comprising a coil, means for producing a magnetic field, a member 10 of non-magnetic material having supporting surfaces lying in a common plane, a pole piece rigidly secured to said member and having pole faces lying in the plane of said supporting surfaces, an armature disposed adjacent to said pole faces, a cutting tool connected with said 15 armature, and means for suspending said armature from the supporting surfaces of said member.

4. An electromagnetic device comprising a coil, means for producing a magnetic field, two members of non-magnetic material having supporting 20 surfaces, the supporting surfaces of each member lying in a common plane, a pole piece rigidly secured to each of said members and having pole faces lying in the plane of the supporting surfaces of their respective member, an armature disposed 25 adjacent to said pole faces, and means for flexibly suspending said armature from the supporting surfaces of said member, said means being clamped between the supporting surfaces of said members.

5. An electromagnetic device, comprising a coil, means for producing a magnetic field, a member 30 of non-magnetic material having supporting surfaces lying in a common plane, a pole piece rigidly secured to said member and having pole faces 35 lying in the plane of said supporting surfaces, a flat piece of magnetic material of uniform thickness suspended from the supporting surfaces of said member with the interposition of spacers, said flat piece serving as an armature and as a 40 flexible suspension therefor.

6. An electromagnetic device comprising a coil, means for producing a magnetic field, two U-shaped members of non-magnetic material, each member having two supporting surfaces lying in 45 a common plane, a pole piece rigidly secured to each of said members and having two pole faces lying in the plane of the supporting surface of its respective non-magnetic member, a flat piece of magnetic material having a uniform thickness, 50 said piece having an armature portion, suspension portions and intermediate torsional portions, spacers between said suspension portions and the supporting surfaces of said non-magnetic members to space the armature portion from said pole 55 faces, and means for clamping said non-magnetic members, spacers and flat piece together.

ROELOF VERMEULEN.
